UNITED STATES PATENT OFFICE

CHARLES H. OSLUND, OF WORCESTER, MASSACHUSETTS, ASSIGNOR TO THE LIQUID CARBONIC CORPORATION, OF CHICAGO, ILLINOIS, A CORPORATION OF DELAWARE

LABEL DATING DEVICE

Application filed January 7, 1930. Serial No. 419,170.

This invention relates particularly to a device, constituting a part of a labeling machine, for operating upon the labels on the back, dating them, or otherwise stamping them, so that at some subsequent time the date on which they were applied, or the operator applying them, or any other information desired, can be obtained or for other purposes.

10. The principal objects of the invention are to provide a construction, preferably constituting part of a labeling machine, in which an element is provided operating on an ungummed surface of each label between the two 15 pickers usually employed; to provide means for actuating the element with the proper sequence to provide a date or other stamp on the back of each label preferably near the center thereof; to provide this construction 20 so coordinated with the pickers that it constitutes very little additional mechanism to the mechanism ordinarily employed for picking purposes, and thus entails comparatively little expense, and to provide an arrangement for this purpose involving comparatively few motions.

Other objects and advantages of the invention will appear hereinafter.

Reference is to be had to the accompanying 30 drawings in which

Fig. 1 is a side view of a labeling machine constructed in accordance with this invention, provided with a dating device;

Fig. 2 is an end elevation of the machine 35 showing the mechanism for operating the dating means particularly;

Fig. 3 is a horizontal sectional view on the line 3—3 of Fig. 1, showing the inking of the dating stamp;

40. Fig. 4 is a view similar to Fig. 3, but showing the inking roller retracted;

Fig. 5 is a diagrammatic view showing the operation of inking the dating stamp and applying it to the label, and

45. Fig. 6 is a side view of the inside of a part of the inking device taken in the direction of the arrow 6 in Fig. 4.

The invention is shown in a form in which it involves a labeling machine of a type now 50 well known. This machine comprises a

power shaft 10 delivering power through gears, not shown, to a rotary table 13 carrying the bottles 14, or other articles to be labeled, around in a circle.

The ordinary pickers 15 are spaced apart and apply gum or paste to each label in two spots near the opposite ends. These pickers are mounted to swing and slide on a rod, operated by a cam 17 on the shaft 10. This cam as usual operates a lever 18, pivoted on a stud 34, and an adjustable link 19 connected with an arm 20 which, with the holder 21 of the pickers 15, constitutes a lever pivoted on the rod 16. These elements are shown for the purpose of operating these pickers back and forth. They are also operated along the rod 16 by a cam 22 on the shaft 10, lever 23 and a grooved element 24 secured to the frame 21 on which the pickers are mounted. These parts are all old.

It is also old to supply paste or gum to the pickers from a gumming roll 25 which is reciprocably mounted in inclined guides 26 and moves up and down the pickers. The means for operating this roll 25 is not illustrated. It is also old for these pickers to move forward toward the label holder after the roll 25 has descended beyond their ends and to engage the labels L between the label holder fingers 28 and take it away as shown in dotted lines in Fig. 4.

On the shaft 16 is an arm 30 having an extension 31. This arm is swung on the rod 16 by a cam 32 on the shaft 10, a lever 33 pivoted on the stud 34 and an adjustable link 35. These parts, it will be seen, operate in the same way as the corresponding parts for operating the side or end pickers 15.

A dating stamp 37 is employed on the extension 37 to date or otherwise identify the labels on the back. The date is stamped on the labels at a point between the two areas of gum provided by the pickers 15, in other words, on an ungummed area. It is placed on the labels where it is entirely concealed ordinarily so that if anything goes wrong with the labels after the goods are sold, the date or the number of the operator can be identified by taking the labels off.

The dating stamp 37 is operated by the

cam 32. It is not moved into contact with the gumming roll but is moved into contact with the labels in the label holder as indicated in Fig. 4. Instead of being moved into contact with the gumming roll, means is provided for supplying the stamp with ink. This means comprises a cam 40 on the shaft 10 operating a lever 41, link 42, and bell crank 43. On the end of this bell crank 10 is adjustably mounted a frame 44. It can be adjusted longitudinally in a slot 45 and moved pivotally and held there by screws 46. On the end it is provided with an inking roll 47. Now the operation of the cam 40 moves 15 this roll from the position shown in Fig. 4, in which it is receiving ink, to the position shown in dotted lines in Fig. 5, in which it is inking the die or type pad 37 and back again.

The ink is supplied from a fountain 50, 20 which can be filled as desired, and has a valve 51 which is adjusted to allow the ink to descend a drop at a time on the outer surface of a vertical roll 52. This roll is freely supported in a bearing on a bracket 53 by means 25 of an arm 54 and adjusted in proper position so that the drops will fall on its surface. The roll 47 is also vertical and as it comes back into the picker stand 55 in which the roll 52 is located, it will engage the surface of the 30 roll 52 and rotate both rolls on their own axes so that with the continued motions they will both perform complete rotations eventually and the roll 47 will be inked.

The operation is obvious. When the pickers 35 15 move up to the gumming roll and receive gum on their surface, the dating stamp 37 is held back away from it so that it will not receive any gum. At a later stage it is advanced slightly and the roll 47 brought into 40 contact with it to ink it, as shown in dotted lines in Fig. 5. Then the stamp moves forward against the label in a dry spot after the gumming roll has descended out of the way. The parts are retracted as indicated in Figs. 45 4 and 5 and in a similar way to that shown on the first two figures.

This provides a simple way of dating or otherwise stamping the backs of labels without adding any great amount of mechanism 50 to the machine and that in such position that it is found to coact in proper sequence with the rest of the operations and is not likely to get out of place or out of order. In this way 55 the dating mechanism can be added to the existing machine at very little expense and without appreciable additional cost for rearrangements and repairs.

Although I have shown and described only 60 one form of the invention and shown both of them as applied to a particular type of labeling machine, I am aware of the fact that modifications can be made in the particular form shown and that it can be applied, with or without modifications, to other types of 65 labeling machines without departing from

the scope of the invention as expressed in the claims. Therefore, I do not wish to be limited to all the details of construction herein shown and described or to the particular form of labeling machine, but what I do claim is:—

1. In a printing device for a labeling machine, the combination with an oscillatable shaft having an arm thereon, a printing stamp carried by said arm, means for swinging said shaft to bring the stamp into contact with a label, an inking roll, an oscillatable arm on which the inking roll is mounted, and means for moving said oscillatable arm to move the inking roll across the printing surface of the stamp when the stamp is retracted away from the label to prepare the stamp for the next printing operation. 70

2. In a label printing device, the combination with a printing stamp and means for moving the stamp forward and back to apply it to the rear or inner surface of the label in an unpasted portion thereof, an oscillating shaft, an inking roll carried by said oscillating shaft, means for turning the shaft to bring the inking roll into contact with the printing surface of said stamp when it is drawn back away from the labels, and an ink supplying roll in position for the inking roll to be brought into contact with it when the inking roll is retracted for supplying the inking roll with ink. 80

3. In a label dating device, the combination with a main shaft, two cams on the shaft, a dating stamp, means operated by one of said cams for moving the dating stamp into contact with a label and back again, an inking device comprising a shaft having an arm thereon, an inking roll on said arm in position to move across the type face of the stamp upon the oscillation of the shaft, and means operated by the other cam for oscillating the last named shaft. 100

4. In a label dating device, the combination with a stamp for dating the labels and means for moving it into and out of contact with them, of a main shaft, a second shaft, means for oscillating said second shaft as the first shaft rotates, an arm adjustably mounted on the second shaft, an inking roll on said arm in position to move across the face of the type on the stamp during the oscillation of the second shaft, an inking roll in position to be engaged by the first roll when it is retracted, the second roll being freely rotatable on its own axis, and means for inking the second roll. 110

5. In a label dating device, the combination with a stamp for dating the labels; and means for moving it into and out of contact with the labels, of a main shaft, a cam on the shaft, a second shaft, means controlled by said cam for oscillating said second shaft as the first shaft rotates, an arm adjustably mounted on the second shaft, an inking roll on said arm in position to move across the 120 125 130

face of the type on the stamp during the oscillation of the second shaft, said roll being mounted to turn on a vertical axis on said arm, an inking roll also mounted on the vertical axis in position to be engaged by the first roll when it is retracted, the second roll being freely rotatable on its own axis and adjustable, and means for causing ink to drop on the cylindrical surface of the second roll, whereby as the two rolls come into contact time after time the ink will be spread out on them.

10 In testimony whereof I have hereunto affixed my signature.

15 CHARLES H. OSLUND.
